(57) CLAIM

The ornamental design for a vertical phone pouch without flap, as shown and described.

DESCRIPTION

FIG. 1 is a front isometric view of the vertical phone pouch without flap, shown in use;

FIG. 2 is a front isometric view thereof;

FIG. 3 is a front isometric view;

FIG. 4 is a front elevation view thereof;

FIG. 5 is a rear elevation view thereof;

FIG. 6 is a right side elevation view thereof;

FIG. 7 is a left side elevation view thereof;

FIG. 8 is a top plan view thereof; and,

FIG. 9 is a bottom plan view thereof.

The broken lines depict environmental structure and are included for the purpose of illustration only and form no part of the claimed design.
